UNITED STATES PATENT OFFICE.

THOMAS R. COOK, OF PITTSBURGH, PENNSYLVANIA.

DESIGN FOR A TERMINAL CONNECTOR FOR SECONDARY BATTERIES.

6,650.

Specification for Design.

Patented Nov. 23, 1920.

Application filed August 10, 1920. Serial No. 402,693. Term of patent 14 years.

To whom it may concern:
Be it known that I, THOMAS R. COOK, a citizen of the United States, residing at Pittsburgh, in the county of Allegheny and state of Pennsylvania, have invented a new, original, and ornamental Design for a Terminal Connector for Secondary Batteries, which the following is a specification, reference being had to the accompanying drawings, forming part thereof.

In the drawing:

Figure 1 is a top plan view of the terminal connector; Fig. 2 is a side plan view thereof, and Fig. 3 is a bottom plan view of the connector.

I claim:

The ornamental design for a terminal connector for secondary batteries, as shown.

THOMAS R. COOK.
